UNITED STATES PATENT OFFICE

ARTHUR B. PUTZEL, OF PHILADELPHIA, PENNSYLVANIA, ASSIGNOR TO QUAKER CITY CHOCOLATE & CONFECTIONERY CO., OF PHILADELPHIA, PENNSYLVANIA, A CORPORATION OF PENNSYLVANIA

CANDY POLISHING MACHINE

Application filed May 14, 1931. Serial No. 537,469.

This invention relates to new and useful improvements in polishing machines and has for its primary object to provide an effective polishing machine for chocolate coated candies or the like.

Another object of the invention is to provide a machine of the stated character having the polishing elements thereof disposed in a novel manner to effectively and completely polish every piece of candy traveling thereunder.

Another object of the invention is to provide a device of the stated character which may be adjusted for candies of various sizes.

Another object of the invention is to provide a machine which may be adjusted to increase or decrease the friction existing between the polishing elements and the candies.

Another object of the invention is to provide a device of the stated character which may be readily transported from one candy distributing machine to another.

Another object of the invention is to provide a device of the stated character wherein the polishing elements may be rotated at various speeds as desired.

Another object of the invention is to provide a device of the stated character wherein the polishing elements may be readily removed or replaced for cleaning or other purposes.

The invention further resides in certain novel features and details of construction set forth hereinafter and shown in the accompanying drawings, in which:

Figure 1 is a view in elevation of the machine constituting the invention;

Fig. 2 is a sectional view on line 2—2, Fig. 1;

Fig. 3 is an enlarged detail view in perspective showing the means for mounting the polishing elements on the machine;

Fig. 4 is an enlarged sectional view on line 4—4, Fig. 1, showing the construction utilized in connection with the polishing elements with the power source; and

Fig. 5 is a detached view in perspective of one of the uprights supporting the polishing mechanism.

In the candy industry, after having been coated with chocolate or other similar material, the candy is carried on coated sheets of paper or other material, by means of conveyors to a point of concentration for sorting and packing. Heretofore the coating on the candies has been polished manually during the travel thereof on the conveyors. Such a practice takes a considerable amount of time, labor, and furthermore, is substantially ineffective to produce the desired luster. By my invention, I provide a machine which may be disposed above and transversely of the conveyors carrying the candies and which may be adjusted vertically with respect to the candies passing therebelow, effectively polishing the said candies in considerably faster time and reducing the amount of labor required.

A particular feature of my invention resides in the manner in which I dispose the polishing elements, the operating functions and features of which will be discussed at length hereinafter.

Referring to the drawings, a machine made in accordance with my invention comprises a pair of spaced upright supports 1, 1 each having a horizontal base portion 2, and outwardly extending lugs 3 and 4 respectively, the purpose for which will be set forth hereinafter. The supports 1, 1 are each further provided with a vertical groove 5 disposed intermediate the extending lugs 3 and 4 respectively. The supports 1, 1 may be secured to guide rails 6, disposed adjacent each side of the belt conveyor 7 and parallel with respect thereto, by any suitable means such as bolts 8.

A cross head 9, having the central portion thereof removed as shown in Fig. 1, is provided with lugs 10 extending outwardly from the ends of the said cross head and adapted to extend through the vertical slots 5 formed in the upright supports at which point the said extensions 10 are threaded on a hand screw 11 rotatably secured in the outward extensions 3 and 4 of the uprights 1, 1 respectively. The removal of the hand screw 11 from the supports is prevented by the adjustable collars 12, the upper faces of

which abut the under face of the extending lugs 3. It will be noted that by turning of the hand screws 11 by the handles 13 at the upper ends thereof, the cross head 9 may be raised or lowered as the operator of the machine desires.

A plurality of shafts 14 are vertically and rotatably mounted in the cross head 9 as shown in Fig. 4, of the drawings, the said shafts extending a suitable distance below the cross head. The polishing elements which, in the present instance are ordinary stock brushes consisting of goat hair bristles 15 secured in a wooden handle or base 16, are mounted in clips 17 which are secured at the lower ends of the shafts 14. The clips 17 in the present instance have a plurality of depending fingers 18 adapted to effectively grip the under surface of the brush base 16 and are further provided with a spring strip 19 by means of which sufficient pressure is applied to the top of the brush base 16 to normally prevent the removal of the brush resting on the depending fingers 18 from the holder and yet, will permit the easy removal thereof when it is desired to cleanse or replace the worn brushes. The brush clips 17 are secured to the lower extremity of the shafts 14 by means of a collar 20 centrally located on the upper surface of the brush clip 17, the said collar 20 being secured on the shaft 14 by the set screw 21.

A gear 22 is rigidly mounted on each of the shafts 14 in the cut-out portion of the cross head 9, the teeth 23 of each of the said gears 22 being in interlocking engagement with the teeth of the gear wheels disposed adjacent thereto. To effectively rotate the polishing elements, I extend one of the shafts 14 a suitable distance above the upper surface of the cross head 9 and secure a parallel friction plate 24 at the upper extremity thereof by means of a set screw 25. Connection between the friction plate 24 and a motor 26 is accomplished by means of a friction element 27 rigidly mounted on the shaft 28 of the motor 26, the said friction element contacting with the upper face of the friction plate 24 and effectively imparting rotation thereto which rotation is transmitted by means of the gear elements 22 to each of the polishing elements.

As stated above the particular feature of my invention resides in the novel arrangement of the clips adapted to receive the polishing brushes, the said clips being positioned in such a manner that the paths, described by the rotation thereof, intersect and at the same time no contact between adjacently disposed elements being possible, and it should be pointed out that such an arrangement of the said elements is essential to the effective operation of the machine made in accordance with my invention. By so positioning the polishing elements, every piece

of candy passing thereunder on the coated sheets of paper carried by the conveyors is acted upon by at least one of the said elements, a substantial number of times, regardless of the position of the candy on the conveyor. During the passage of the candy beneath the polishing elements, every contact of the polishing elements with a piece of the candy is at a different angle from the previous contact, thus producing a polish that is uniform, highly effective, and gives a greater luster to the product.

Also by my invention I am able to utilize polishing element which are stock articles on the open market and effecting considerable economy.

While I have described a particular embodiment of my invention for the purpose of description it will be apparent that certain modifications and changes in the detailed construction thereof may be incorporated without departing from the spirit of the invention.

I claim:

1. In a candy polishing machine, the combination with a belt conveyor of a pair of spaced uprights adjacent each side of said conveyor, a horizontal cross head mounted on said uprights, means for vertically adjusting the cross head with respect to the conveyor, a plurality of vertically disposed shafts rotatably mounted in said cross head, a gear rigidly mounted on each of said shafts and in interlocking engagement with the adjacently positioned gears, an elongated spring clip mounted at the lower end of each of the shafts, arranged for rotation with said shafts and having the described paths thereof intersecting, a polishing element secured in each of said clips, a motor mounted on the cross head, and friction means for synchronously rotating said elements to prevent contact of any two of said elements.

2. In a candy polishing machine, a pair of spaced uprights, a horizontal cross head mounted on said uprights, means for vertically adjusting the cross head with respect to the conveyor, a plurality of vertically disposed shafts rotatably mounted in said cross head, a gear rigidly mounted on each of said shafts and in interlocking engagement with the adjacently positioned gears, an elongated spring clip mounted at the lower end of each of the shafts, arranged for rotation with said shafts and having the described paths thereof intersecting, a polishing element secured in each of said clips, a motor mounted on the cross head, and friction means for synchronously rotating said elements to prevent contact of any two of said elements.

3. In a candy polishing machine, the combination with a belt conveyor of a pair of spaced uprights adjacent each side of said conveyor, a horizontal cross head mounted on said uprights, a plurality of vertically dis-

- posed shafts rotatably mounted in said cross head, a gear rigidly mounted on each of said shafts and in interlocking engagement with the adjacently positioned gears, an elongated spring clip mounted at the lower end of each of the shafts, arranged for rotation with said shafts and having the described paths thereof intersecting, a polishing element secured in each of said clips, a motor mounted on the cross head, and friction means for synchronously rotating said elements to prevent contact of any two of said elements.
4. In a candy polishing machine, the combination with a belt conveyor of a pair of spaced uprights adjacent each side of said conveyor, a horizontal cross head mounted on said uprights, means for vertically adjusting the cross head with respect to the conveyor, a plurality of vertically disposed shafts rotatably mounted in said cross head, an elongated spring clip mounted at the lower end of each of the shafts, arranged for rotation with said shafts and having the described paths thereof intersecting, a polishing element secured in each of said clips, a motor mounted on the cross head, and friction means for synchronously rotating said elements to prevent contact of any two of said elements.
5. In a candy polishing machine, a pair of spaced uprights, a horizontal cross head mounted on said uprights, a plurality of vertically disposed shafts rotatably mounted in said cross head, a gear rigidly mounted on each of said shafts and in interlocking engagement with the adjacently positioned gears, an elongated spring clip mounted at the lower end of each of the shafts, arranged for rotation with said shafts and having the described paths thereof intersecting, a polishing element secured in each of said clips, a motor mounted on the cross head, and friction means for synchronously rotating said elements to prevent contact of any two of said elements.
6. In a candy polishing machine the combination with a conveyor of, a pair of spaced uprights, a horizontal cross head mounted on said uprights, means for vertically adjusting the cross head with respect to the conveyor, a plurality of vertically disposed shafts rotatably mounted in said cross head, an elongated spring clip mounted at the lower end of each of the shafts, arranged for rotation with said shafts and having the described paths thereof intersecting, a polishing element secured in each of said clips, a motor mounted on the cross head, and friction means for synchronously rotating said elements to prevent contact of any two of said elements.
7. In a candy polishing machine, a pair of spaced uprights, a horizontal cross head mounted on said uprights, a plurality of vertically disposed shafts rotatably mounted in
- said cross head, an elongated spring clip mounted at the lower end of each of the shafts, arranged for rotation with said shafts and having the described paths thereof intersecting, a polishing element secured in each of said clips, a motor mounted on the cross head, and friction means for synchronously rotating said elements to prevent contact of any two of said elements.
8. In a candy polishing machine, the combination with a conveyer, of a pair of spaced uprights, a horizontal cross head mounted on said uprights, means for vertically adjusting the cross head with respect to the conveyer, a plurality of vertically disposed shafts rotatably mounted in said cross head, a gear rigidly mounted on each of said shafts and in interlocking engagement with the adjacently positioned gears, a polishing element secured at the lower end of each of the shafts, a motor mounted on the cross head, and friction means connecting the motor with the gears for synchronously rotating said elements to prevent contact of any two of the elements.
9. In a candy polishing machine the combination with a conveyer, of a pair of spaced uprights, a horizontal cross head mounted on said uprights, means for vertically adjusting the cross head with respect to the conveyer, a plurality of vertically disposed shafts rotatably mounted in said cross head, a gear rigidly mounted on each of said shafts and in interlocking engagement with the adjacently positioned gears, an elongated polishing element mounted at the lower ends of each of the shafts arranged for rotation therewith and having the described paths thereof intersecting, and a motor mounted on the cross head constituting a source of power for rotating said elements.
